BRITISH COLUMBIA, CANADA

SELF-UNLOADING LOG BARGE

Application filed June 21, 1928, Serial No. 287,103, and in Canada February 13, 1928.

The invention relates to improvements in self unloading log barges, as described in the present specification and illustrated in the drawings that form part of the same.

5 The invention consists essentially of the novel arrangement and construction of parts, wherein a barge having a specially constructed keelson extending above the deck thereof is adapted to have extending 10 towers therefrom, said towers having mounted at the top thereof a suitable shaft extending longitudinally the length of the barge; the said barge is provided with a plurality of hinged stanchions along each 15 side, each of said stanchions having a guy wire secured thereto and removably connected to aforesaid shaft, the said stanchions through suitable chains removably secured at the bottom thereof adapted to permit of 20 same acting as a binding element in normal operation. The deck of the barge has suitable tapering declined skids extending from the aforementioned keelson on either side thereof.

25 The objects of the invention are to devise a log barge, the construction and positioning of the elements thereof adapted to permit of ease and quickness in loading, tightly binding the load in transit, and to 30 permit of quickness in self unloading from alternate sides. A further feature is the construction of a rigid and strong barge.

Referring to the drawings:

Figure 1 is a side elevation view of barge.

35 Figure 2 is a plan view of barge.

Figure 3 is a cross sectional view of barge.

Figure 4 is a detail view of mobile portion of stanchion hinge.

40 Figures 5, 6, 7 and 8 are views showing the position of barge during oscillatory listing.

Figure 9 is a detail view of stationary portion of stanchion hinge.

Figure 10 is a detail of a boom arm.

45 Figure 11 is a detail of stanchion in normal position.

Figure 12 is a detail of boom arm in operating position.

50 Figures 13 and 14 are cross sectional views of unloading shaft.

In the drawings like numerals of reference indicate corresponding parts in each figure.

1 represents a barge of any suitable lines, having a center keelson 2 extending above the deck 3 as at 4; the said keelson has secured thereto and extending upwardly therefrom and spaced apart a plurality of any desired number of towers 5, the said towers adapted to have mounted at the top a shaft 6, said shaft extending centrally the length of said barge and having suitable connections at the bow thereof to some prime mover, adapted to cause the said shaft to revolve, the purpose of which will later be explained.

Secured to the deck in spaced pairs are a plurality of tapered declined skids 7 extending from the keelson 2 toward either side of the barge. Between the said skids are hingedly secured stanchions 8 by means of a special hinge comprising a mobile portion 9 secured to the outside of the stanchion and provided with two oppositely disposed lugs 10, the stationary portion 11 secured to the deck and provided with an eye 12.

The stanchions 8 are held in normal upright position by means of a pair of chains 13, secured at one end in the eye 12, the opposite ends engaging the aforesaid lugs 10 of the mobile portion 9.

55 A guy wire 14 is provided one to each stanchion adapted to extend and be removably connected to the aforementioned shaft 6 by means of an eye of suitable design engaging a hook 15, said hook 15 positioned on the shaft one opposite to each stanchion, the guy wire on one side of the barge being of greater length than those on the other side, adaptable upon rotation of shaft 6 in one direction, to tighten said wires and upon reverse rotation of shaft, to release all guy wires on one side and upon further rotation in same direction, to release all guy wires on opposite side, due to the difference in length of said wires.

At present logs are transported either by means of rafts which are very costly to construct and unwieldy to tow, or in ordinary barges requiring time and labor in unloading, consequently we have devised our barge

to overcome these defects, the operation of which will now be explained.

The stanchions being in normal position upright, and held in this position by the chains 13 engaging the lugs 10 of the stanchion hinge, the logs are conveyed from the water or siding to the deck skids and piled until a full load is attained and it will readily be seen that by the chains 13 engaging the 10 stanchions in angular position, that the log lying next to said stanchions will cause the tightening of said chains bringing the stanchions into binding engagement whereby the load is tightly and rigidly held in position, 15 the said load being divided by means of the extending portion 4 of the keelson. Having loaded the barge, the guy wires 14 on either side are secured to the shaft and the said shaft revolved sufficiently to tighten 20 same, the said tightening of the wires making a further binding of the stanchions.

Having transported the barge full of logs to its destination, the operation of unloading is as follows: the chains 13 are disengaged from the lugs 10 on both sides of the barge, and the shaft revolved in contrawise manner until the tension on one side has been released to free the eyes of the wires from the shaft hooks, whereupon the stanchions on that side will fall outwardly and downwardly into the water then acting as buffers to protect the sides of the barges from the released and falling logs, and it will readily be seen that the logs when released, will be assisted in their unloading by the tapered declined skids, the further revolving of the shaft in the same direction will release the wires on the other side in like manner aforementioned, the barge having listed to the opposite side due 40 to the lightening of the load through the first release of the logs, and it will be seen that by the releasing in alternate operations will cause an oscillatory listing until the entire load is disposed of, whereupon the barge 45 will assume the position as shown in Figure 8, but with the stanchions and wires in the water at the side of the barge, and to aid in bringing the said stanchions from this position to their normal upright position, we 50 provide a boom arm 20 pivotally secured between the skids, having suitable tackle operating thereon, whereby the said stanchions may be raised.

It will be seen that we have devised a barge having a center keelson adapted to strengthen the barge and divide the load, suitable means connected to a rotatable shaft adapted to allow of quick unloading of the barge, thereby reducing the time and labor in unloading to a minimum.

We claim:

1. In self unloading log barges, in combination, a barge having a center keelson adapted to extend above the deck thereof, a plurality of shaft supporting towers, secured

to and extending above the said keelson and spaced one from the other, adapted to have mounted thereon a rotatable shaft, said shaft having suitable hooks secured thereon and spaced one from the other, a plurality of tapered declining skids, extending from the keelson toward either side of the barge, arranged in spaced pairs, a plurality of hinged stanchions positioned within said skids, the mobile portion of the hinge having oppositely disposed lugs formed thereon, and the stationary portion of the hinge being provided with an eye, a pair of chains, secured to said eye of each stationary hinge, and removably secured to the lugs of the mobile portion of the hinge in an angular manner, cables secured at one end to stanchions and engaging through suitable eyes the hooks on the shaft, said cables upon rotation of aforesaid shaft adapted to be tightened and bind the aforesaid stanchions to the load.

2. In self unloading log barges, in combination, a barge having a center keelson, adapted to extend above the deck thereof, a plurality of shaft supporting towers secured to and extending above the said keelson and spaced one from the other, adapted to have mounted thereon a rotatable shaft, said shaft having suitable hooks secured thereon and spaced one from the other, a plurality of tapered declining skids extending from the keelson toward either side of the barge arranged in spaced pairs, a plurality of hinged stanchions positioned within the pairs of skids, the mobile hinge portion having oppositely disposed lugs formed thereon and the stationary hinge portion having an eye formed thereon, a pair of chains secured to said eye of stationary hinge portion and removably secured to the lugs of the mobile portion in angular manner, cables secured at one end to aforesaid stanchions, engaging through suitable eyes the hooks on aforesaid shaft, all the cables on one side of the barge 110 adapted upon rotation of shaft to be released, and upon further reverse rotation of shaft to release all cables on opposite side, said release of cables adapted to permit of aforesaid stanchions to fall to side of 115 barge and act as buffers, and also causing a disturbent state of trim whereby a controlled sequence of oscillatory listing takes place, a plurality of boom arms pivotally secured between aforesaid pair of skids 120 adapted through suitable tackle to assist in raising stanchions to normal upright position.

3. In self-unloading log-barges, in combination, a barge having a center keelson 125 adapted to extend above the deck thereof, a plurality of shaft supporting towers secured to and extending above the said keelson in spaced apart relation and having mounted thereon a rotatable shaft, a plurality of de- 130

clined transverse skids extending from each side of said keelson to each side of the barge, a plurality of hinged stanchions in spaced apart relation positioned along the deck in alignment and adjacent each side of said barge, cables secured at one end to said stanchions and being at the other end in releasable engagement with said shaft whereby upon rotation of the shaft the cables in connection with the stanchions on one side of the barge are simultaneously released and upon further rotation of the shaft in the same direction the cables connected with the stanchions on the other side are similarly released and the said stanchions allowed to fall to the side of the barge and act as buffers, and whereby the sequential release of the cables and stanchions first on one side and then on the other results in an unstable condition of trim, thus setting up a controlled sequence of oscillatory listings thus permitting the load of logs to automatically and gradually unload into the water on each side.

4. In self-unloading log-barges, in combination, a barge having a centre keelson adapted to extend above the deck thereof, a plurality of shaft supporting towers secured to and extending above the said keelson in spaced apart relation and having mounted thereon a rotatable shaft, a plurality of declined transverse skids extending from each side of said keelson to each side of the barge, a plurality of hinged stanchions in spaced apart relation positioned along the deck in alignment and adjacent each side of said barge, cables secured at one end to said stanchions and being at the other end in releasable engagement with said shaft whereby upon rotation of the shaft the cables in connection with the stanchions on one side of the barge are simultaneously released and upon further rotation of the shaft in the same direction the cables connected with the stanchions on the other side are similarly released and the said stanchions allowed to fall to the side of the barge and act as buffers, and whereby the sequential release of the cables and stanchions first on one side and then on the other results in an unstable condition of trim, thus setting up a controlled sequence of oscillatory listings thus permitting the load of logs to automatically and gradually unload into the water on each side, a plurality of boom arms projecting beyond the side of said barge and adapted through suitable tackle to assist in raising the said stanchions to their normal upright position.
